LOCKING LUG NUT

Arthur Duane Hale, Sr., Rolling Hills, Calif.
(800 Santiago, Long Beach, Calif. 90804)

Filed Aug. 9, 1974, Ser. No. 496,043

Term of patent 14 years
The term of this patent subsequent to Mar. 18, 1989,
has been disclaimed

Int. Cl. D8—08

U.S. Cl. D8—273

FIG. 1

FIG. 2

FIG. 4

FIG. 3

FIG. 5

FIG. 1 is a perspective view of a locking lug nut showing my new design;

FIG. 2 is a side view thereof, in enlarged scale;

FIG. 3 is a right hand end view thereof, in enlarged scale;

FIG. 4 is a back view thereof, in enlarged scale; and

FIG. 5 is a left hand end view, in enlarged scale.

I claim:

The ornamental design for a locking lug nut, substantially as shown and described.
